UNITED STATES PATENT OFFICE.

THEODORE H. WURMB AND ROBERT BAUMANN, OF ST. LOUIS, MISSOURI.

ELECTRIC TOWER-CLOCK.

SPECIFICATION forming part of Letters Patent No. 585,301, dated June 29, 1897.

Application filed May 18, 1896. Serial No. 591,993. (No model.)

To all whom it may concern:

Be it known that we, THEODORE H. WURMB and ROBERT BAUMANN, of the city of St. Louis, State of Missouri, have invented certain new and useful Improvements in Electric Tower-Clocks, of which the following is a full, clear, and exact description, reference being had to the accompanying drawings, forming a part hereof.

10 Our present invention relates to the construction of electromechanical clocks of large dimensions, such as sign and tower clocks, and the mechanism for operating said clocks, and also the system of electrically operating 15 such mechanism.

The object of our invention is to provide a machine of the most simple construction, positive in its operation under all conditions and circumstances, and the most economical 20 in the use of the electric current supplying the power. Following out this general object, we have constructed a device which may be operated with less electric current than would be required to even start the armature of an 25 electric motor of a size capable of operating the clock.

In the drawings, Figure 1 is a top plan view of our improved mechanism for operating tower-clocks. Fig. 2 is a side elevation of the 30 parts shown in Fig. 1. Fig. 3 is a vertical transverse sectional view on the lines 3 3 of Fig. 1, looking in the direction as indicated by the arrow. Fig. 4 is a vertical transverse sectional view on the lines 4 4 of Fig. 1, looking in the direction as indicated by the arrow. Fig. 5 is an elevation, partly in section, of 35 our improved tower-clock and our improved mechanism for operating the same. Fig. 6 is a transverse sectional view on the lines 6 6 of Fig. 1. Fig. 7 is a diagrammatic view 40 showing the course of the electric currents through the mechanism of our improved tower-clock and the connections between said mechanism and the master-clock. Fig. 8 is 45 a side elevation showing an enlarged detail view of the electrical connections to the master-clock and its location relative to the shaft of the seconds-hand of said clock. Fig. 9 is a top plan view of the part shown in Fig. 8. 50 Referring to the drawings by numerals, the power mechanism is mounted on the table 1. Transversely-aligned posts 2 project upwardly

from near the center of said table 1, and in bearings in said posts is journaled the shaft 3, upon which is mounted the worm-gear 4 55 between said posts. Below the table 1 and attached thereto are brackets 5 and 6, and in the lower ends of said brackets are longitudinally-aligned bearings in which is mounted the shaft 7, upon the center of which is positioned the worm-gear 8, which meshes into and is driven by the worm-gear 4, as shown in Fig. 6.

Near one end of the shaft 3 and outside of the bearings 2 is fixed a ratchet-wheel 9. Two 65 non-magnetic brass brackets 10 and 11 are secured to the table 1 and project upwardly therefrom and carry two horseshoe electromagnets 12 and 13, one above the other and in a horizontal position. At the ends of the 70 magnets 12 and 13, opposite the brackets 10 and 11, are non-magnetic brass brackets 14 and 15, and a shaft 16 is journaled in the upper ends of said brackets and transversely of the machine.

Vertical bars 17 and 18 are attached at 75 their centers to the shaft 16, and the upper ends of said bars are connected by the armature 19 of the electromagnet 12, and the lower ends of said bars are connected by the armature 20 of the electromagnet 13. A pawl 21 is attached to the end of the armature 19 by the screw 22 and extends longitudinally of the machine and engages the teeth of the ratchet-wheel 9, and a similar pawl 23 is attached to the end of the armature 20 by a screw 24, and also engages the teeth of the ratchet-wheel 9.

By a system of alternating currents, which will be explained later, the armatures 19 and 90 20 are attracted alternately, thus imparting a rocking motion to the bars 17 and 18 and the shaft 16, and by this means the pawl 21 is pulled backwardly when the pawl 23 is pushed forwardly, and vice versa. This rocking motion operates the ratchet-wheel 9 and imparts motion to the worm-gear 4 and through its connections to the clock in the tower. The teeth of the ratchet-wheel 9 are preferably one-eighth of an inch apart and 95 of an even number. The range of motion between the armatures and the face of the cores is proportionate to the distance between the teeth of the ratchet-wheel. The pawl of 100

that armature opposite that one which is being attracted pushes the ratchet-wheel a distance equal to one-half of a tooth, and consequently it requires two motions of each armature, one 5 backward and one forward, to push the ratchet-wheel the distance of one tooth. By switching the electric current in such a way as to cause the armatures to operate alternately a continuous vibrating motion is imparted to said armatures and through the pawls and their connections to the clock, as 10 before described.

The table 1 is preferably made of iron, and behind the brackets 10 and 11 a base 25, made 15 of slate or marble, is rigidly secured to said table 1. There is an opening of suitable size in the table 1 underneath the base 25 for suitable electrical connections with the different parts mounted on said base.

20 A lug 26 is secured to the inner face of the lower armature 20, and a bar 27 is pivotally connected to said lug 26 and extends longitudinally of the device and between the coils of the lower magnet 13 to a position above 25 the base 25. In the rear end of the bar 27 is a pin 28, projecting upwardly through the slot 29 in the free end of the switch-lever 30, as shown in Fig. 1. There is a sliding connection between the rear end of the bar 27 30 and the base 25. A plate 31 is secured to the base 25, and a pin 32 passes downwardly through the end of the switch-lever 30 and the plate 31 and is fixed in the base 25. Upon the upper surface of the switch-lever 30 and surrounding the pin 32 is a collar 33, 35 and on top of said collar is a washer 34, and on top of said washer 34 is a spring-washer 35, and on top of said spring-washer is a nut 36, by means of which the pressure upon the 40 switch-lever 30 is regulated. The free end of said switch-lever 30 is provided with an upwardly-projecting lug 37, carrying the longitudinally-extending horizontal contact-pin 38, said pin being provided at each end with 45 platinum contact-points 39 and 40.

The mechanism just described is necessarily very finely adjusted. The bar 27 travels backwardly and forwardly about one-eighth of an inch, or a distance equal to the 50 vibration of the armatures, but by means of the slot 29, in which the pin 28 operates, there is lost motion between the bar 27 and the free end of the switch-lever 30, which allows the armatures to almost strike the cores before 55 the pin 28 moves the switch-lever 30. Mounted upon the opposite end of the base 25 from the pin 32 are binding-posts 41 and 42, to which are attached copper contact-springs 43 and 44, said springs being horizontally positioned 60 transversely of the machine and having their free ends adjacent to the platinum contact-points 39 and 40, as shown in Fig. 1. Posts 45 and 46 are positioned between the free ends of said springs 43 and 44, and set-screws 47 and 48 are screw-seated in said posts 45 and 46 in a horizontal position with the points of said screws against the inner

faces of the ends of said springs, and the distance between the ends of said springs is adjusted and determined by said set-screws. 70 The switch-lever 30 and the parts connected to it are of brass or bronze. The sides of the slot 29 are protected from the strokes of the pin 28 by a hardened-steel plate 49, having a corresponding slot, which steel plate is secured to the switch-lever 30. The length of the slot 29 is approximately one-sixteenth of an inch less than the range of motion of the armatures plus the thickness of the pin 28. The bar 27 is cut in two on the dotted 80 lines 27^a and a piece of insulation 27^b is inserted to connect the two ends of said bar and thus insulate the pin 28 from the lug 26.

The copper springs 43 and 44 are so adjusted relative to the contact-points 39 and 40 that when the point 39 is in contact with the spring 44 the point 40 is out of contact with the spring 43, and vice versa.

The operation of the bar 27 by the armatures operates the switch-lever 30 through the 90 pin 28, working in the slot 29, and thus operates the pin 38 to alternately break the circuit attached to the spring 43 and close the circuit attached to the spring 44, and vice versa. If the lower armature be moved by 95 hand slowly against the core of its magnet, the pin 28 pushes the switch-lever 30 backward, connecting the contact-point 39 with the spring 44 and disconnecting the contact-point 40 from the spring 43, and the switch-lever remains in this position under pressure of the spring-washer 35. If the upper armature be moved against its magnet, the contact-point 39 leaves the spring 44 and the point 40 connects with the spring 43 and is 100 held there by the pressure of the spring-washer 35 until the lower armature is moved again.

In adjusting the springs 43 and 44 with relation to the contact-points 39 and 40 the 110 switch-lever 30 is placed in its central position, and then by means of the set-screws 47 and 48 the springs 43 and 44 are adjusted to press lightly against the contact-points 39 and 40. When a connection has been adjusted in this way, the operation of the switch-lever 30 pushes the one of the copper springs which is in contact with one of the points away from the set-screw controlling that 115 spring, as shown in Fig. 1. The set-screw controlling the opposite spring holds the spring which rests against that set-screw from following the pin 38 in its travel. Mounted upon the table 1, upon the opposite side of the post 2 from the mechanism just described, is a 120 bracket 50, which carries the electromagnet 51 and forms the yoke of said magnet, the coils of said magnet being arranged one above the other. The magnet 50 acts as a relay, its operation closing the circuits which operate 125 the magnets 12 and 13. The bracket 50 extends upwardly to a point above the upper edge of the magnet 51 and then longitudinally of said magnet to a point in front of the

cores of said magnet. The armature 52 is pivotally connected to the upper end of the bracket 50 in position to be operated by the cores of the magnet 51. Attached to the upper surface of the bracket 50 is a binding-post 53, through which operates the screw 54, which screw is controlled by the nut 55, and to the head of the screw 54 is attached a retractile coil-spring 56, which spring is attached at its opposite end to the bar 57, which bar is attached to and projects upwardly from the armature 52. The tendency of the coil-spring 56 is to pull the armature 52 away from the faces of its core.

15 Mounted upon the shaft 3, adjacent to the ratchet-wheel 9, is a disk 58, having a notch 59 cut in its periphery. A ratchet tooth or lug 60 is attached to the front face of the armature 52 and is designed to engage the notch 59 in the disk 58. Pivotaly attached to the outer face of the disk 58 by the screw 61 is an A-shaped dog 62, the large end of which extends outwardly from the axis of the disk. A pin 63, projecting outwardly from the face 20 of said disk 58, limits the motion of said dog 62 in a forward direction, and the edge of said dog strikes against the hub 64 of the disk 58 to limit its motion in a backward direction. Projecting outwardly from the face 25 of said dog is a pin 65, designed to be engaged by the lever 66, which is pivoted to the armature 52.

30 Projecting upwardly at an angle from the pivot of the lever 66 is a short arm 67, in which is mounted a pin 68, designed to engage the back side of the armature 52, and thus limit the downward motion of the free end of the lever 66. On the lower surface of the lever 66 is a ratchet-tooth 69, designed to 35 engage the pin 65 on the dog 62. Assuming that the ratchet-tooth 60 is in the slot 59, then the dog 62 will be in a vertical position with one side resting against the hub 64 of the disk 58 and the ratchet-tooth 69 will be in 40 contact with the pin 65 on the dog 62, as shown in Fig. 2. When the mechanism is in this position, the armature 52 is held out of contact with the core of the magnet 51 by the tension of the spring 56 acting upon the lever 45 57. When the magnet 51 is energized, the armature 52 is attracted against the face of its cores, and this motion of the armature moves the ratchet-tooth 69 quickly toward the magnet 51, and by this motion the dog 52 55 62 has its large end moved away from the hub 64 and out of a vertical line and by the force of gravity is carried downwardly until it strikes the pin 63. When in this position, the outer face of the dog 62 rests against the face 60 of the armature 52 beside the lug 60 and holds said armature against the cores of the magnet 51 until the disk is rotated to such an extent that the ratchet-tooth 60 rests upon the circular periphery of the disk 58 and is out 65 of engagement with the notch 59.

Projecting from the lower end of the armature 52 and in a position parallel with the

shaft 3 is a pin 70, upon the outer end of which is mounted a hard-rubber collar 71. Near the opposite end of the shaft 3 from the pin 70 and approximately in line therewith a post 72 is vertically positioned, and a spring-arm 73 is attached to said post and has its free end normally in engagement with the rubber collar 71 on the pin 70. Between the post 72 and the magnet 51 is mounted a binding-post 74, in which is transversely positioned a set-screw 75, and a pin 76 is longitudinally positioned in said binding-post and designed to be engaged by the inner end of the set-screw 75. Upon the point of the pin 76 is a platinum contact-point 77, adjacent the spring-arm 73. Electric wires are attached to the table 1 by the posts 72 and 74, and the connection between said wires is 80 made through the spring-arm 73 and the platinum point 77, and said connection is broken or closed by the action of the armature 52 operating the pin 70 and the collar 71 and thereby vibrating the free end of the spring-arm 73 against and away from the platinum point 77, as shown in Fig. 1.

Upon the shaft 7 to the left of the worm-gear 8 is mounted a bevel-gear 78, which meshes into a bevel-gear 79. Extending upwardly from the table 1 upon the side of the magnet 51 opposite the shaft 3 is a bracket 80, carrying the vertically-aligned bearings 81 and 82, in which is mounted a shaft 83.

Upon the lower end of the shaft 83 and below the bearing 82 is a collar 84, fixed to said shaft, and immediately below said collar is a collar 85, rotatably mounted upon said shaft, and the bevel-gear 79 is fixed to the lower end of said collar. Immediately above the hub 95 of the gear 79 and fixed to the collar 85 is a disk 86, in the periphery of which are evenly-spaced recesses, preferably sixty in number. An arm 87 projects horizontally from the collar 84 to a position in vertical alinement with the periphery of the disk 86, in the outer end of which is a vertically-positioned pin 88, designed to engage the recesses in the periphery of the disk 86, thus forming a connection between the shaft 7 through the bevel-gears 78 100 and 79, the collar 85, the disk 86, the pin 88, the arm 87, and the collar 84 to the shaft 83. Upon the upper end of the shaft 83 is a bevel-gear 89, meshing into the bevel-gear 90 upon the shaft 91, which shaft operates a dummy 105 clock of ordinary construction. (Not shown.) Upon the extreme upper end of the shaft 83 is a universal joint 92, connecting with the shaft 93, and upon the upper end of said shaft 93 is a second universal joint 94, connecting 110 with the central gearing of the clock mechanism, as shown in Fig. 5.

In order to give properly-spaced electrical impulses to the mechanism heretofore described, we employ a master-clock, which 115 may be located in any desired place and connected by electric conductors with the clock mechanism. For this purpose we place upon the front plate 95 of the clock-frame the block

of rubber 96, which block is attached to the clock-frame by the screws 97 and 98, working in the slots 99 and 100 in said rubber block. Attached to the outer end of said block 96 is a bar 101, in the lower end of which is positioned a screw 102, to which the end of a conductor is attached. At the upper end of the bar 101 are the lugs 103 and 104, between which is mounted the nut 105, and a screw 106 is positioned horizontally through said lugs and said nut. To one of the outer ends of said screw 106 is attached a leaf-spring 107, which rests upon the upper surface of said block 96 and projects beyond the end of said block. A lug 108 projects upwardly from said block 96 to a point over the spring 107, and a set-screw 109 is screw-seated in said lug with its point engaging the upper surface of said spring 107. By means of the screw 109 the pressure of the spring 107 against the upper surface of the block 96 may be regulated, and by means of the nut 105 operating between the lugs 103 and 104 upon the screw 106 the position of the free end of said spring 107 may be finally adjusted.

A tube 110 is mounted upon the seconds-hand shaft 111 of the clock. Platinum points 112 and 113 project in opposite directions from said tube 110, and the under surface of the free end of the spring 107 has a thin sheet of platinum and is so positioned that a contact is made between said spring 107 and the platinum points 112 and 113, one each half-minute.

When the seconds-hand upon the master-clock passes the minute-mark, the contact-point 112 engages with the end of the spring 107, the contact lasting a fraction of a second, during which time part of the electric current passes from the battery 114 along the wire 115, and from said wire 115 through the wire 116 to the frame 95 of the master-clock, and through the tube 110, the contact-point 112, the spring 107, and through the wire 117 to the coils of the magnet 51. The armature 52 is then attracted to the cores of the magnet 51, and this motion of the armature 52 carries the free end of the spring 73 into contact with the platinum point 77. Making this contact closes the circuit through the magnets 12 and 13 and the current passes from the battery 114 over the wire 115 to the binding-post 118, which is attached to the plate 31, then through the pin 32 to the switch-lever 30, then through the pin 38 and from the contact-point 40 to the spring 43, to the post 41, thence through the wire 119 to the coils of the magnet 13, which energizes the cores of said magnet and attracts the armature 20, the motion of which pushes the bar 27 to operate the switch-lever 30 away from the magnet 13, thus breaking the contact between the point 40 and the spring 43 and making the contact between the point 39 and the spring 44. Then the current passes through the spring 44 to the post 42, and through the wire 120 to the magnet 12, which energizes the cores of said

magnet and attracts the armature 19, which movement pulls the bar 27 forward, moving the switch-lever 30 to break the contact between the point 39 and the spring 44 and renew the contact between the point 40 and the spring 43. When the platinum points upon the seconds-hand shaft of the master-clock contact with the spring 107, a part of the current, as before suggested, passes to the coils of the magnet 51, but as soon as this contact is broken the full force of the battery is directed through the magnets 12 and 13. The continued vibration of the armatures 19 and 20 act through the pawls 21 and 23 to rotate the ratchet-wheel 9, thus rotating the worm-gear 4, and through its connections operating the hands of the clock in the tower. From the magnet 12 the current passes to the binding-post 121 through the wire 122, and from the magnet 13 the current passes to said binding-post 121 through the wire 123, and from said binding-post said current passes through the wire 124 to the binding-post 72, thence through the spring 73, through the point 77, through the pin 76, and thence through the wire 125 to the opposite pole of the battery 114. From the coils of the magnet 51 the current passes through the wire 126 to the binding-post 74 and thence through the wire 125 to the opposite pole of the battery 114. Then the magnet 51 attracts the armature 52, as hereinbefore described, pulling the dog 62 out of balance and allowing it to drop down against the pin 63. Said dog 62 holds said armature 52 against the cores of the magnet 51 until the ratchet-tooth 60 passes out of the notch 59 and rests upon the periphery of the disk 58, as hereinbefore described. This operation holds the circuit leading to the magnets 12 and 13 closed and in operation until the disk 58 has made a complete revolution, thus permitting the ratchet-tooth 60 to again drop into the notch 59, thus allowing the spring 56 to operate upon the bar 57 and pulling the armature 52 away from the cores of the magnet 51 and thus break the circuit to the magnets 12 and 13, when the mechanism will come to a standstill until the platinum points upon the shaft of the seconds-hand again contact with the spring, when the operation is repeated, as heretofore described.

There is lost motion between the points of the pawls 21 and 23 and the teeth with which they engage, which allows the armatures operating said pawls to come close to their respective cores before operating the shaft 3. This gives the armatures a chance to get under motion, and the result is a very strong pull or push upon said pawls. The movement of the seconds-hand shaft of the master-clock controls the current which operates the magnet 51, and the movement of the armature 52 by the attraction of the magnet 51 and by the action of the dog 62 and the disk 58 controls the current which operates the magnets 12 and 13. If it is desired that the clock

shall be operated only once a minute, then but one of the platinum points 112 and 113 is needed; but, on the contrary, if it is desired to operate the clock every fifteen seconds 5 four of said points would be required. If the clock and its connections to the shaft 3 are so geared that one revolution of the disk 58 moves the minute-hands of the clock one minute and it is desired to move them oftener 10 than once a minute, and consequently not so far at a movement, it is necessary that the disk 58 be constructed with notches 59, directly opposite each other, and with two of the dogs 62. This will operate the clock 15 every half-minute and move the hands accordingly. If it is desired to change the construction to operate the clock every fifteen seconds, the disk 58 should be constructed with four of the notches 59 and four of the 20 dogs 62.

The dog 62 operates entirely by gravity, except that it is given an overbalancing impulse by the ratchet-tooth 69 when the armature 52 is attracted. When the dog 62 is passing upwardly in its orbit, it is the force of gravity that brings it against the hub 64, and it is so constructed that it leans by gravity against said hub until overbalanced in the opposite direction, as before described.

30 The hands upon the dummy clock attached to the shaft 91 are in the same position relative to their dial as are the hands of the display-dials. Thus the operator in charge of the clock may know by looking at the dummy 35 clock just what indication appears upon the display-dials. If it is desired to change this indication—*i. e.*, set the clock ahead or backward—the operator removes the pin 88 from engagement with the disk 86, and the connection between the shaft 7 and the shaft 83 40 is thus broken, and by operating the arm 87 the clock may be set as desired, and then the pin 88 is again inserted in the disk 86 and the connection is again established.

45 In the construction of the mechanism herein shown and described insulation may be applied wherever it is found necessary or beneficial, and we do not deem it necessary to particularize in this respect further than we 50 have done.

We prefer to make the worm-wheel 8 with one hundred and twenty teeth, two teeth for each minute-space upon the dial of the clock, and then one revolution of the worm 4 will 55 rotate the worm-wheel 8 the distance of one tooth, and thus move the minute-hand of the clock the space of one-half a minute. This gives the worm 4 great power and enables it to operate a large clock under all conditions 60 and circumstances. With this construction it is necessary that the magnets should receive an impulse from the master-clock every half-minute, as before described.

We claim—

65 1. In an electric clock, a switch connected to and operated by rocking armatures, which

switch consists of a lever pivoted at one end, a bar connected to the rocking armatures and operating transversely of the free end of said lever, a pin fixed in the end of said bar and 70 operating in the slot in the free end of said lever, a lug attached to the free end of said lever, a pin transversely fixed to said lug, contact-points upon the opposite ends of said pin, springs fixed to the base of the machine 75 by posts, the free ends of said springs being positioned adjacent said contact-points, set-screws for adjusting the free ends of said springs, and suitable electrical connections, substantially as specified. 80

2. In an electric clock, a switch connected to and operated by rocking armatures, which switch consists of a lever pivoted at one end, a bar connected to the rocking armatures and operating transversely of the free end of said 85 lever, said bar consisting of two pieces of metal connected together by a piece of insulation, a pin fixed in the end of said bar and operating in the slot in the free end of said lever, a lug attached to the free end of said 90 lever, a pin transversely fixed to said lug, contact-points upon opposite ends of said pin, springs fixed to the base of the machine by posts, the free ends of said springs being positioned adjacent to said contact-points, set-screws for adjusting the free ends of said 95 springs, the nut and spring washer for regulating the pressure upon the pivoted end of said lever, and suitable electrical connections, substantially as specified. 100

3. In an electric clock, the combination, with rocking armatures, of a switch consisting of the bar 27 attached to the rocking armatures, said bar consisting of two metallic ends joined together by insulation 27^b and the rear end of 105 said bar having a sliding connection with the base, the pin 28 projecting upwardly from the rear end of said bar 27, the switch-lever 30 pivotally mounted upon the base and having the slot 29 in its free end in which said pin 28 110 operates, the upwardly-projecting lug 37 upon the free end of said switch-lever 30, the contact-pin 38 attached to said lug and the springs 43 and 44 adjustably held in position to be engaged by said contact-pin, substantially as 115 specified.

4. In an electric clock, a switch to be operated by rocking armatures, consisting of the switch-lever 30, the plate 31 under one end of said switch-lever, the pin 32 passing downwardly through the end of said switch-lever and through said plate and fixed in the base, a collar 33 upon said pin and engaging the upper surface of said switch-lever, the washer 34 on top of said collar, the spring-washer 35 120 on top of said washer 34, the nut 36 on top of said spring-washer, the upwardly-projecting lug 37 upon the free end of said switch-lever, the contact-pin 38 attached to said lug, the platinum contact-points 39 and 40 upon 125 the ends of said pin, the springs 43 and 44 adjustably held in position to be engaged by 130

said contact-points, and means of operating the free end of said switch-lever, substantially as specified.

5. In an electric clock, a switch to be operated by rocking armatures, consisting of the switch-lever 30, the plate 31 under one end of said switch-lever, the pin 32 passing downwardly through the end of said switch-lever and through said plate and fixed in the base, the collar 33 upon said pin and engaging the upper surface of said switch-lever, the washer 34 on top of said collar, the spring-washer 35 on top of said washer 34, the nut 36 on top of said spring-washer, the upwardly-projecting lug 37 upon the free end of said switch-lever, the contact-pin 38 attached to said lug, the platinum contact-points 39 and 40 upon the ends of said pin, the springs 43 and 44 adjustably held in position to be engaged by said contact-points, means of operating the free end of said switch-lever, which means consist of a bar 27 attached to rocking armatures and having a sliding connection with the base, the pin 28 projecting upwardly from the rear end of said bar through the slot 29 in the free end of said switch-lever 30, and insulation between the two ends of said bar 27, substantially as specified.

6. In an electric clock, a switch operated by rocking armatures, consisting of the binding-posts 41 and 42 fixed to the base, the contact-springs 43 and 44 fixed to said binding-posts substantially in parallel position, the posts 45 and 46 positioned between the free ends of said springs, the set-screws 47 and 48 screw-seated respectively in said posts 45 and 46 with the points of said screws against the inner faces of the free ends of said springs, the switch-lever 30 pivoted with its free end between the free ends of said springs, the lug 37 attached to the free end of said switch-lever, the contact-pin 38 attached to said lug, the ends of said contact-pin being in position to engage the free ends of said springs, and means of operating said switch-lever, substantially as specified.

7. In an electric clock, a pair of electromagnets mounted one above the other, armatures in position to engage the cores of said magnets, a rocking connection between said armatures, a switch attached to and operated by said armatures for the purpose of alternating the current between said magnets, which switch consists of a pivotally-mounted lever having a slot in its free end, a bar connected to the rocking armatures and having a pin in its free end to engage said slot, a contact-pin mounted upon the free end of said switch-lever, and leaf-springs mounted in position to be alternately engaged by said contact-pin, substantially as specified.

8. In an electric clock, a pair of electromagnets mounted one above the other, armatures in position to engage the cores of said magnets, a rocking connection between said armatures, a switch attached to and operated by said armatures for the purpose of alternating

the current between said magnets, which switch consists of a pivotally-mounted lever having a slot in its free end, a bar connected to the rocking armatures and having a pin in its free end to engage said slot, a contact-pin mounted upon the free end of said switch-lever, and leaf-springs mounted in position to be alternately engaged by said contact-pin, one of said leaf-springs being electrically connected to the upper magnet and the other one of said leaf-springs being electrically connected to the lower magnet and said switch-lever being electrically connected with the battery, and set-screws for adjusting the free ends of said springs relative to said contact-pin in such a way that but one spring will be in contact with the pin at a time, substantially as specified.

9. In an electric clock, the electromagnets 12 and 13, the brackets 14 and 15 in front of said magnets, the shaft 16 journaled in the upper ends of said brackets, the vertical bars 17 and 18 attached to said shaft, the armature 19 connecting the upper ends of said vertical bars, the armature 20 connecting the lower ends of said vertical bars, the switch-bar 27 attached to one of said armatures and the switch-lever 30 connected to said bar, substantially as specified.

10. In an electric clock, a pair of electromagnets mounted one above the other, armatures in position to engage the cores of said magnets, a rocking connection between said armatures, reciprocating pawls operated by said armatures in opposite directions, a worm mounted in front of said armature, a ratchet-wheel upon the shaft of said worm and in position to be rotated by said pawls, and a switch attached to said armatures whereby the current is alternated between said magnets, which switch consists of a lever pivoted at one end, a bar connected to the rocking armatures and operating transversely of the free end of said lever, said bar consisting of two pieces of metal connected together by a piece of insulation, a pin fixed in the end of said bar and operating in the slot in the free end of said lever, a lug attached to the free end of said lever, a pin transversely fixed to said lug, contact-points upon opposite ends of said pin, springs fixed to the base of the machine by posts, the free ends of said springs being positioned adjacent to said contact-points, set-screws for adjusting the free ends of said springs, and the nut and spring-washer for regulating the pressure upon the pivoted end of said lever, substantially as specified.

11. In an electric clock, a pair of electromagnets mounted one above the other, armatures in position to engage the cores of said magnets, a rocking connection between said armatures, reciprocating pawls operated by said armatures in opposite directions, a worm mounted in front of said armature, a ratchet-wheel upon the shaft of said worm and in position to be rotated by said pawls, a switch

attached to said armatures whereby the current is alternated between said magnets, and connections between said worm and the hands of a clock whereby said hands are operated by the operation of said armatures, which connection consists of the bracket 80 having the vertically-alined bearings 81 and 82, the shaft 83 mounted in said bearings, the collar 84 fixed to said shaft below the bearing 82, the collar 85 loosely mounted upon said shaft immediately below the collar 84, the bevel-gear 79 fixed to the lower end of said collar 85, the disk 86 fixed to the upper end of said collar 85, said disk having evenly-spaced recesses in its periphery, the arm 87 projecting horizontally from the collar 84, the pin 88 in the outer end of said arm and in position to engage the said recesses, means of operating said bevel-gear 79 and connections between said shaft 83 and the hands of the clock, substantially as specified.

12. In an electric clock, a pair of electromagnets mounted one above the other, armatures in position to engage the cores of said magnets, a rocking connection between said armatures, reciprocating pawls operated by said armatures in opposite directions, a worm mounted in front of said armature, a ratchet-wheel upon the shaft of said worm and in position to be rotated by said pawls, a switch attached to said armatures whereby the current is alternated between said magnets, a disk mounted upon the shaft of said worm, said disk having a notch in its periphery, a dog pivotally connected to the face of said disk and positioned with its free end to operate adjacent to said notch, a pin projecting from said free end, an armature vertically positioned with its free end adjacent to the periphery of said disk, a tooth upon said armature and in position to engage the notch in said disk, a pawl pivotally attached to said armature with its free end in position to engage said pin upon said dog, substantially as specified.

13. In an electric clock, a pair of electromagnets mounted one above the other, armatures in position to engage the cores of said magnets, a rocking connection between said armatures, reciprocating pawls operated by said armatures in opposite directions, a worm mounted in front of said armature, a ratchet-wheel upon the shaft of said worm and in position to be rotated by said pawls, a switch attached to said armatures whereby the current is alternated between said magnets, a disk mounted upon the shaft of said worm, said disk having a notch in its periphery, a dog pivotally connected to the face of said disk and positioned with its free end to operate adjacent to said notch, a pin projecting from said free end, an armature vertically positioned with its free end adjacent to the periphery of said disk, a tooth upon said armature and in position to engage the notch in said disk, a pawl pivotally attached to said armature with its free end in position to en-

gage said pin upon said dog, and connections between said worm and the hands of a clock whereby said hands are operated by the 70 operation of said armatures, substantially as specified.

14. In an electric clock, reciprocating pawls attached to rocking armatures, a ratchet-wheel mounted upon a shaft in a position to 75 be rotated by said reciprocating pawls, a worm mounted upon the shaft of said ratchet-wheel, a disk mounted upon said shaft and adjacent said ratchet-wheel, said disk having a notch in its periphery, a dog pivotally connected to 80 the face of said disk and positioned with its free end to operate adjacent to said notch, a pin projecting from said free end, an armature vertically positioned with its free end adjacent to the periphery of said disk, a tooth 85 upon said armature and in position to engage said notch in said disk, a pawl pivotally attached to said armature with its free end in position to engage said pin, a pin projecting from the free end of said vertical armature, 90 a block of insulation upon the outer end of said pin, a binding-post, a leaf-spring attached to said binding-post with its free end in engagement with said block of insulation and a contact-point in position to be engaged 95 by the free end of said spring when said spring is operated by the attraction of said armature, substantially as specified.

15. In an electric clock, a contact-point carried by the shaft of a master-clock, a spring 100 in position to be engaged by said contact-point at each revolution of said shaft, a block of rubber attached to the front plate of the master-clock, adjustable connections between said block of rubber and said spring, whereby said 105 spring is supported and may be adjusted, a vertically-positioned electromagnet connected by suitable conductors to said spring, a vertical armature operated by said magnet, a pin carried by the free end of said armature, a 110 block of insulation upon the free end of said pin, a leaf-spring engaging said insulation, a contact-point adjacent the free end of said spring and in position to be engaged by said 115 spring when said spring is operated by the attraction of said armature, and conductors attached to said contact-point and to said spring, substantially as specified.

16. In an electric clock, an adjustable connection between the motive power and the 120 hands of a clock, which connection consists of the bracket 80 having the vertically-alined bearings 81 and 82, the shaft 83 mounted in said bearings, the collar 84 fixed to said shaft below the bearing 82, the collar 85 loosely 125 mounted upon said shaft immediately below the collar 84, the bevel-gear 79 fixed to the lower end of said collar 85, the disk 86 fixed to the upper end of said collar 85, said disk having evenly-spaced recesses in its periphery, the arm 87 projecting horizontally from the collar 84, the pin 88 in the outer end of said arm and in position to engage the said 130 recesses, means of operating said bevel-gear

79 and connections between said shaft 83 and the hands of the clock, substantially as specified.

17. In an electric clock, the block of rubber 5 96 adjustably attached to the front plate of a master-clock, the bar 101 attached to the outer end of said block, the screw 102 in the lower end of said bar, the lugs 103 and 104 at the upper end of said bar, the nut 105 mounted 10 between said lugs, the screw 106 positioned horizontally through said lugs and said nut, the leaf-spring 107 attached to one end of said screw and resting upon the upper surface of said block, the lug 108 projecting upwardly 15 to a point over the said spring 107, the set-

screw 109 screw-seated in said lug with its point engaging the upper surface of said spring, the tube 110 mounted upon the seconds-hand shaft of the clock, and platinum points projecting from said tube in position 20 to contact with the free end of said spring, substantially as specified.

In testimony whereof we affix our signatures in presence of two witnesses.

THEODORE H. WURMB.
ROBERT BAUMANN.
